UNITED STATES PATENT OFFICE.

ROBERT T. BOURN, OF TEMPLETON, MASSACHUSETTS.

POST-OFFICE FURNITURE.

1,152,275.

Specification of Letters Patent. Patented Aug. 31, 1915.

Application filed September 9, 1912. Serial No. 719,407.

To all whom it may concern:

Be it known that I, ROBERT T. BOURN, a citizen of the United States, residing at Templeton, county of Worcester, and State of Massachusetts, have invented an Improvement in Post-Office Furniture, of which the following description, in connection with the accompanying drawing, is a specification, like characters on the drawing 10 representing like parts.

This invention relates to post-office furniture of that type which is commonly used by letter carriers in sorting and routing their mail. This type of post-office furniture comprises a table above which is situated a routing case comprising shelves having partitions to divide them into compartments.

Some of the objects of my invention are to provide a novel form of table top which 20 can be made extensible to provide additional room in sorting paper or package mail, and also to provide an arrangement of compartments on the table top in which the paper mail can be sorted and faced, thus avoiding 25 the necessity of placing the paper mail after it is sorted on the high shelves of the case, as is necessary to do with some types of assorting cases; and further to provide a novel construction of assorting case and 30 shelves and partitions therefor by which letters will be more accurately maintained in their vertical position, and can be more readily inserted into the various compartments; to provide a novel construction of 35 assorting case which facilitates the bundling up of the mail after it has been sorted; to provide a novel form of base or standard for the assorting case which is sanitary and which can be readily taken down and packed 40 in a small space; and otherwise to improve post-office furniture of this nature, all as will be more fully hereinafter described and pointed out in the appended claims.

Referring now to the drawings wherein I 45 have shown some embodiments of my invention Figure 1 is a vertical section on substantially the line $x-x$ Fig. 2; Fig. 2 is a front view of an assorting case embodying my invention; Fig. 3 is a section on the line 50 $y-y$, Fig. 2; Fig. 4 is an enlarged section on the line $a-a$, Fig. 2; Fig. 5 is a section on the line $b-b$, Fig. 4; Fig. 6 is a detail of the pivotal support for the shelf back; Fig. 7 is a sectional view through the cap piece 55 of the standard; Fig. 8 is a section on the line $c-c$, Fig. 1; Fig. 9 is an enlarged sec-

tion on the line $d-d$, Fig. 8; Fig. 10 is a section on the line $e-e$, Fig. 9; Fig. 11 is an enlarged transverse section through one of the shelves; Fig. 12 is a front view of a portion of one of the shelves; Fig. 13 is an enlarged section on the line $f-f$, Fig. 8; Fig. 14 is a detail of the support for the shelves; Fig. 15 is a view similar to Fig. 1, showing a different form of the invention; Fig. 16 is a front view of the Fig. 15; Fig. 17 is a section on the line $g-g$, Fig. 16; Fig. 18 is a view similar to Fig. 1, showing a double case involving one embodiment of my invention; Fig. 19 is a perspective view of a portion of a shelf back showing a manner of securing the partitions thereto; Fig. 20 shows a different manner of securing the partitions to the shelf back; Fig. 21 is a plan view showing the movable compressor 75 of the paper facing slide illustrated in Fig. 18; Fig. 22 is a section on the line $h-h$, Fig. 18; Fig. 23 is a section on the line $z-z$, Fig. 18; Fig. 24 is a perspective detail view showing a slightly different form of shelf 80 support.

My device comprises a frame 1 adapted to support a plurality of shelves 2, each of which is provided with partitions to divide them into compartments. This frame 1 is 85 supported on a base piece 3 which in turn is sustained by a suitable standard. The base piece 3 also sustains a movable table top 5 which will be more fully hereinafter described.

Referring first to the standard, this has been devised to provide a sanitary knock-down structure, and this end is secured by making the standard of metal, and in such a way that it can be readily taken down and packed in a small space for storage or shipment. The improved standard herein shown comprises a base 6, a post or pedestal 7 sustained thereby, and a plurality of arms 8 connected to the upper end of the post 7 100 and secured to the underside of the base-board 3. The base 6 is shown as a casting provided with a central screw-threaded socket 9 and the post 7 is shown as a tubular member screw-threaded at its lower end into the opening 9. The base 6 is preferably formed with the depending interior flange 10 which forms a continuation of the hub or upwardly-extending flange 11, the flanges 10 and 11 providing a comparatively long 105 opening 9 to receive the lower end of the post 7. I will preferably screw-thread the

lower portion only of said opening 9 and will provide a set-screw 12 in the flange 11 which is adapted to engage the post 7 and lock it in adjusted position. The post 7 can be adjusted vertically in the case 6 thereby to adjust the height of the table top 5 by merely loosening the set-screw 12 and then screwing said post up or down as desired.

The top of the post 7 sustains a cap piece 13 to which the arms 8 are secured. These arms may either be detachably secured to said cap piece or may be made integral therewith. In Figs. 1, 2 and 3 I have shown a construction wherein the arms are detachably secured to the cap piece, thereby making a knock-down construction. In Figs. 15 to 17 I have shown a construction wherein the arms are integral with the cap piece. Referring first to the construction shown in Figs. 1, 2 and 3 it will be seen that the cap piece is provided with a flange 14 having a plurality of apertures 15 formed therein, and that the arms 8 are offset slightly at their lower ends, as at 16, so that these offset ends may be inserted through the slots 15 and thus held in place, as clearly seen in Figs. 1 and 2. The upper ends of the arms 8 are secured to the base piece 3 by any suitable means, such as screws or bolts. The cap 13 is provided with a recess 17 to receive the upper end of the post 7 and with a shoulder herein formed by inwardly-extending fingers 18 which rests on the upper end of the post. 19 is a set screw for locking the cap piece to the post. When the table is to be adjusted vertically the set-screw 19 has to be loosened as well as the set-screw 12, so as to permit the post 7 to turn in the cap 13, as well as in the base 6. When the proper adjustment has been secured both set-screws 12 and 19 are set tight and the standard will then become a rigid structure. When an assorting case of this nature is loaded with mail the center of the weight comes at a point back of the center of the table top 5, and where the device is supported on a single post, as herein shown, it is desirable to have this post located as nearly as possible under the center of the weight, so that the structure will be evenly balanced. The construction shown in Figs. 1, 2 and 3 permits this to be done, for the apertures 15 are sufficiently large so that the arms 8 can be swung laterally somewhat, and in setting up the piece of furniture, I propose to spread the rear arms 8 to a greater degree than the front arms, as clearly shown in Fig. 3. In order to facilitate the manufacture, I propose to make all the arms 8 from the same pattern and the upper ends of the rear arms will come at the rear corners of the base 3, while the upper ends of the front arms will come at a point inside of these corners. In Fig. 3 the arrangement of arms 65 is shown and also the table top in outline,

and by the construction illustrated it is possible to set the post 7 somewhat in the rear of the center of the base 3 and in approximately a position corresponding to the center of the weight.

In Figs. 15 to 17 I have shown an embodiment of the invention wherein the arms 8 are made integral with the cap piece 13. In this construction the socket 17 formed in the cap piece is closed at its upper end as shown at 170, so that the weight of the structure is taken by this part 170. In this embodiment the arms 8 will preferably be so disposed that the post 7 will stand somewhat to the rear of the center of the base-board 3, thereby bringing said post substantially under the center of gravity. The table top 5 is movably mounted on the base-board 3 so that said top may be drawn outwardly into the dotted line position Fig. 1, or may be placed in its retracted position, as shown in full lines Fig. 1. In sorting the letter mail it will be more convenient to have the table top retracted as there will be plenty of room on the front portion thereof to receive all letter mail, and when it is in its backward or retracted position the carrier can reach the shelves 2 with greater facility. In sorting the paper and package mail, however, which is considerably bulky, it is desirable to have the full area of the table top 5 available for use, and by drawing the table top outwardly into the dotted line position this can be accomplished. In order to provide for an easy-movement of the table top when loaded with mail, I propose to employ a pair of rolls 20 in the front of the base 3 and a pair of rolls 21 in the rear of the top 5 on the underside so that said top can roll back and forth on the rolls 20 and 21. 22 is a spring-pressed locking bolt mounted in an opening in the back-board 23 of the top. This locking bolt is adapted to engage a recess 24 in the base-board 3 to lock the table top in its forward position. The bolt is provided with a laterally-extending finger 25 by means of which it may be withdrawn and it is acted on by a spring 26 which tends to force it downwardly into locking engagement with the base 3. The table top 5 is not only provided with the back-board 23 but is provided with the side boards 27. It is also provided with means for dividing the sides thereof into compartments to receive the paper mail as it is sorted, thus avoiding the necessity of placing the package and heavy mail on the high shelves in the frame 1 during the sorting process. These compartments in the table top 5 are provided for by removable partitions 30 which are adapted to be placed at right angles to the sides 27, as seen best in Fig. 8. These partitions are herein shown as provided with a wire rim portion 28 which encircles the sides and top of the body 29 of the partition and 130

which extends down below the lower edge thereof to form feet 31 and 32. The table top 5 is provided with apertures 33 and 34 into which these feet 31, 32 can be set. This 5 provides for placing the partitions at any desired points. The partitions extend transversely of the table or at right angles to the sides 27, as seen in Fig. 4. I will preferably set metal strips 35 into the table top 5 and 10 form the holes 33, 34 in said strips, this construction providing a metal rim for the holes which will prevent any undue wear occurring. The foot 32 of each partition is preferably slightly longer than the foot 31 so 15 that in putting the partition in place the foot 32 may first be entered into the desired hole 34 and then the partition may be swung laterally to bring the foot 31 into alinement with the proper hole 33. This facilitates 20 very much the operation of placing the partitions. At the front side of the table top 5 I provide the swinging arms 36 which are hinged to the sides 27. These swinging arms 36 may be folded back against the sides 25 27 when the table top is being used for sorting letter mail and may be thrown into their operative position shown in Fig. 4 when the partitions 30 are being used. The outer ends of the strips 35 are bent upwardly to 30 form stops 38 against which the swinging arms 36 have engagement when they are in their operative position. When the table top is being used for sorting paper and package mail, straps or tapes 39 may be laid 35 on the table top 5 beneath the partitions 30, said straps being put in place before the partitions are inserted, so that when the mail is placed in the compartments between the partitions 30 it will be placed on the straps 39. When the mail has been completely 40 sorted the partitions 30 may be removed and the two ends of each strap brought together, thus bundling the mail up. I propose to employ hooks 40 in the upper edge of the 45 back side 23 of the top 5 over which hooks the ends of the straps 39 can be placed while the mail is being sorted. The shelves 2 have partitions 42 associated therewith by which they are divided into separate compartments. These partitions are shown as sustained by the backs 43 of the shelves and are made from wire bent into the desired shape, the ends of each wire partition being 50 secured to the backing 43. Each partition is preferably provided on its lower side with a downwardly-directed extension 44 which engages the shelf 2 and which prevents a single letter when inserted into an empty compartment from sliding laterally underneath the partition. Each partition is also 55 preferably formed on its upper side with the inclined portion 45 that terminates in a downwardly-directed portion 46, the portion 46 preferably being situated in the rear 60 portion of the partition. This portion 45, 46 of each partition serves to hold the letters in vertical position and prevents the upper edge of a letter which is occupying a compartment alone from assuming such an inclined position that it will extend over into 70 the adjacent compartment and thus interfere with the insertion of letters therein. The vertical portion 46 is sufficiently near the rear of the compartment so that there is no danger that even a small letter will drop 75 in behind said portion. Moreover, the inclined portion 45 serves as a guide for any letter as it is inserted into the compartment and prevents the upper rear corner of the letter from striking the upright portion 46 80 while the letter is being inserted. The preferred way of securing the partitions 42 to the shelf backing 43 is shown in Figs. 19 and 20.

In the construction shown in Fig. 19 the back 43 is formed on its front face with a longitudinal groove 99 and with a plurality of vertical grooves 98 that intersect the groove 99. The grooves 98 are placed at the points where partitions are desired. The two arms 97 and 96 of each partition are bent 90 at their inner ends to present the vertically disposed portions 95 and the laterally disposed portions 94, the portions 94 of each partition extending in opposite directions 95 and being in alinement with each other. In securing the partition to the backing 43 the vertically disposed portions 95 of any partition are inserted into one of the grooves 98 and the laterally disposed portions 94 are inserted into the groove 99. After all of the partitions have been thus assembled a plate 93 is secured to the front face of the backing 43 so as to overlie the groove 99 and thus hold 100 the partitions firmly in place. The vertical portions 95 hold the partition from turning and maintain it in a vertical plane, and the horizontal portions 94 hold the partition against vertical movement. The plate 93 securely locks all the partitions to the backing. Instead of forming the grooves 98 and 99 on the front face of the backing 43 I may 105 make them on the back side thereof, as shown in Fig. 20. In this case the arms 96, 97 of each partition embrace the backing 43, and the plate 93 is located on the back side of the partition. In other respects, however, the invention is the same as that shown in Fig. 19. This construction is one which admits of rapidly assembling the partitions and the backing and which firmly holds the partitions in place during use. If a small letter happens to lie next to one of the partitions 42, such letter is apt to fall between 110 the upper and lower legs of the partition, and thus interfere with placing of letters into the next adjacent compartment. In order to prevent this from happening I propose to provide each partition with a guard-finger which extends laterally from one of 115 120 125 130

the legs toward the other, preferably at a point between the front and rear edges of the partition. Such guard-finger may be provided for in various ways, but the drawings show the preferred way wherein the lower leg 97 of each partition is bent to form the upwardly directed guard-finger 89. Such guard-finger can be located either in front of or at the rear of the downwardly directed extension 44. In the drawings I have shown the guard-finger as situated immediately in front of said extension. I will preferably make each partition slightly longer than an ordinary business envelop so that even when the compartments are filled with letter mail the front edge of the partitions will be visible beyond the letters and will thus clearly indicate to the letter carrier where the partitions are located. The shelves 2 may be fixed to the backs 43 or may be withdrawable from the backs. In the case of the upper shelves, I prefer to make them separate from the back so that each shelf can be withdrawn from its back and the partitions supported thereby. Where the shelves are made removable from the backs, I propose to adopt the construction shown in Figs. 4-6. The shelf is shown as provided at its back edge with a metal strip 85 constituting a letter stop, this strip extending slightly above the shelf. The back 43 is rabbeted at its lower front edge, as shown at 86 to receive the letter stop so that when the shelf is in its rearward position the front face of the letter stop and the front face of the back are flush with each other. The back is sustained by two holders 47 one at each end thereof, each holder having a channel shape in cross section, as seen in Fig. 5, to receive the end of the back and provided with a stud 48 which sets into the sides of the frame 1 and constitutes a trunnion on which the holder can turn. Each holder 47 also has a pin 49 extending from near the upper edge which works in a slot or recess 50 formed in the sides of the frame 1, said slot being large enough to allow a slight rocking movement to the holder but limiting such rocking movement. Each holder is also provided with the lip 51 at its lower edge on which the back 43 rests. The purpose in pivotally sustaining the holders 47 is to permit the shelf to be removed, for it will be observed that when the shelf is drawn forwardly, the letter stop 85 will engage the extension 44 which is provided with inclined sides and will raise the partitions sufficiently to allow the letter stop to be withdrawn from under said extensions, this raising movement of the partitions giving a rocking movement to the back 43. When the shelves are withdrawn the partitions and back are held in their horizontal position by the engagement of the stop pins 49 with the walls of the recess 50.

I propose to provide means whereby a strap or tape may be laid on each shelf 2 beneath the partitions so that when the letter mail is placed on the shelf it will be laid on the tape. With this construction the mail on any shelf can be readily bundled by simply withdrawing the shelf from the partitions and then bringing the ends of the strap or tape together. This strap or tape is shown at 52 and in order to sustain it in place I provide the vertical wires 53, which constitute both handles for the shelf and end partitions therefor, with the hook portion 54 onto which loops on the end of the tape can be hooked. With this construction the tape can be laid on the shelf while it is removed and then the loops at the ends thereof can be hooked into the hooks 54. The shelf may then be inserted into the case, in doing which the tapes 52 will be carried underneath the partitions 42. When the shelf is filled with mail it may be withdrawn from the case and then the ends of the tape 52 may be gathered together, thus bundling the mail up with great facility. In devices of this nature it is customary to place routing strips 60 on the front edges of the shelves 2 and to hold these routing strips in place I have provided the holders which comprise strips of metal bent into hook shape, as shown at 61, and secured to the front edge of each shelf 2 at suitable intervals (see Figs. 11 and 12). Each holder is shown as having a tang or prong 62 at its upper edge which is driven into the shelf and the finger portion 63 of the holder is more or less resilient and is bent to form a flaring mouth which will permit the ready insertion of the routing strip 60 thereinto and also to present a portion which bears against the strip 105 and frictionally holds it in place.

In the construction shown in Figs. 1 and 2 a drawer 64 is provided beneath the base-board 3 and between the arms 8, this drawer being supported on suitable cleats 65. In some routing cases of this nature two drawers are required beneath the table top, and where this is the case I propose to employ the construction shown in Figs. 15 and 16. In this construction the frame or case 1, which includes the sides, top and bottom 65, is sustained by a base member which comprises the bottom piece 66, the two side pieces 67 rising therefrom and the top piece 68 which extends from one side to the other and is of sufficient depth to reach from the front of the table back to the bottom of the case of the frame 1. In this construction the two pieces 68 and 65 constitute the surface on which the top 5 is mounted. The space between the sides 67 is sufficient to receive two drawers 70. The sides 67 are preferably situated just inside of the side-boards of the case 1, so that these side-boards of the case can be secured to the base by screws 130

71 inserted upwardly through the top 68 on the exterior of the sides 67. This provides a knock-down construction, as the frame 1 can be easily removed from the base member, and the latter can be removed from the arms 8, as will be readily seen.

My invention may be embodied in a double routing case,—that is one adapted to have a carrier working on each side thereof.

10 This routing case comprises the double frame 1, carrying two sets of shelves 2, facing in opposite directions, each shelf having a plurality of partitions 42, all as above described. This frame 1 rests on a double 15 table designated generally at 100, the top 101 of which is divided by the central partition 102 to form the separate spaces for the carriers. In Fig. 18, I have shown an extensible table top section 103, on which 20 the paper mail can be sorted and faced and which may be used in addition to the extensible table top 5 shown in Figs. 1 and 2. In some cases it is desirable to use both the extensible top 5 and the slide 103, and the 25 construction is such that this can be done. In Fig. 18 I have omitted the movable top 5 so as not to confuse the drawings. This table top extension 103 is in the form of a slide which extends the full depth of the 30 double table so that when it is drawn out to its full extent it extends beyond the front of the table top a distance substantially equal to the depth of the double table. This table top extension runs in a suitable runway 104. 35 In order to support the extension or slide 103 when it is fully withdrawn I provide a supporting slide 105 which is adapted to slide back and forth in a runway 106 formed in the table top. This slide has a projection 107 extending from the top thereof which operates in a groove 108 formed in the bottom of the slide 103. The groove is 40 of such a length that when the slide 103 is drawn outwardly the rear end of the groove 45 will strike the projection 107 before the slide is fully extended and will thereafter draw the slide outwardly with it into the position shown in Fig. 18. When the slide is pushed inwardly the opposite end of the slot 50 will engage the projection 107 and will thus carry the supporting slide 105 back into place. The slide 103 supports a movable partition or follower 109, the purpose of 55 which is to provide a space of appropriate size between it and the front wall 110 of the slide. This follower or partition 109 has secured to its under side a locking plate 111 which is provided with an extension 112 having depending flanges 113. These flanges 60 operate in grooves 114 formed in the top of the slide 103. 115 represents a plate or strip secured to the slide 103 between the grooves and having a width to partially overlie the grooves. 116 are screws or headed 65 projections secured in the bottom of the

partition 109 and underlying the edges of the plate 115. These screws or projections 116 not only hold the partition 109 in place on the slide, but allow it to move back and forth. The partition 109 is locked in its adjusted position by merely swinging it 70 slightly to cause it to assume the angular position shown in dotted lines Fig. 21, such movement of the partition carrying the end of one flange 113 and the opposite end of 75 the other flange 113 against the walls of the grooves, thereby producing a binding or locking action which holds the partition from moving.

Another form of shelf support is shown 80 in Fig. 24, wherein one end of the wire 121 is sustained in an eye 161, the other end of said wire being provided with the finger 122 adapted to be driven into the side of the case. The advantage of this construction is 85 that the shelf support is not affected by the swelling and shrinking of the wood.

Another construction embodying my invention is shown in Fig. 18, wherein the shelf supports 121 are carried by swinging 90 suspenders 162. These suspenders are arranged in pairs, there being one pair at each side of the case. Said suspenders are pivotally hung from their upper ends at 163, and the suspenders of each pair are connected by the shelf supports 121. The connection between the shelf supports and the 95 suspenders is one which permits the suspenders to swing back and forth. The holders 47 for the backs 43 are pivoted to 100 one of the suspenders instead of to the side of the frame 1. The advantage of this construction is that the tier of shelves may be 105 swung forwardly or backwardly more or less to bring them into the most convenient position for the letter carrier. The shelf supports will be maintained in horizontal position in all positions of the suspenders. I have shown at 166 spring catches adapted 110 to engage the suspenders and hold them in desired position. A plurality of these catches may be employed if it is desired to provide for holding the suspenders in any one of a plurality of positions. The walls 115 109 and 110 are provided with hooks 120. The purpose of these hooks is to support the ends of a tape 39 which may be laid on the table extension 103 as seen in Fig. 18. As 120 the letter carrier sorts his paper and package mail it is laid on the table and when he is ready to bundle up the mail the ends of the tape are detached from the hooks 120 and tied or otherwise fastened together. The follower 109 may be used on the table top extension 5 if desired, and by illustrating 125 it in connection with the slide 103 I do not wish to be understood as confining its use to the slide. The shelves 2 are shown as sustained by wire shelf supports 121. These shelf supports, one of which is shown in 130

Fig. 14, are made from a piece of wire of the proper length bent at its ends to present fingers 122. The sides of the frame 1 are provided with inclined apertures into which fingers 122 may be received. This makes a very inexpensive but practical support on which the shelf may be slidably sustained.

While I have illustrated herein some embodiment of my invention, I do not wish to be limited to the construction of features shown.

Having fully described my invention, what I claim as new and desire to secure by Letters Patent is:—

15 1. In post-office furniture the combination with a frame, of shelves supported thereby, backs for the shelves, and partitions for dividing the shelves into compartments, each partition being formed of wire bent to present separated top and bottom legs which are secured to the back, one of said legs having a portion bent laterally toward the other leg at a point between the front and rear edges of the partition, thereby to constitute a guard finger which prevents a small letter from entering between said legs.

20 2. In post-office furniture the combination with a frame, of shelves sustained thereby, wire partitions for each shelf, each partition comprising horizontally disposed separated top and bottom legs, one of which has a guard finger extending laterally therefrom toward the other.

25 3. In post-office furniture the combination with a frame, of shelves sustained thereby, wire partitions for each shelf, each partition comprising horizontally disposed separated top and bottom legs, one of which has a guard finger extending laterally therefrom toward the other intermediate of the ends of the partition.

30 4. In post-office furniture the combination with a plurality of shelves, of means to support said shelves, wire partitions dividing each shelf into compartments, each partition comprising horizontally disposed top and bottom legs, the bottom leg having a guard finger extending laterally therefrom toward the other leg.

35 5. In post-office furniture the combination with a plurality of shelves, of means to support the shelves, and partitions dividing each shelf into compartments, each partition being formed of wire and presenting separated top and bottom legs, the wire of the bottom leg being bent intermediate of its ends to present a laterally disposed guard finger which is directed toward the upper leg.

40 6. In post-office furniture the combination with a plurality of shelves, of means to support the shelves, and partitions dividing each shelf into compartments, each partition being formed of wire and presenting separated top and bottom legs, the wire of the

bottom leg being bent intermediate of its ends to present a laterally disposed guard finger which is directed toward the upper leg, and also being bent to present a downwardly directed extension which engages the shelf.

7. In post-office furniture the combination with a plurality of shelves, of means for supporting said shelves, and wire partitions dividing each shelf into compartments, each partition presenting separated top and bottom legs, and the bottom leg of each partition having a guard finger extending upwardly therefrom and an extension extending downwardly therefrom.

8. In post-office furniture the combination with a shelf, of a back therefor, and wire partitions secured to the back, each partition presenting upper and lower separated legs, the upper leg being formed with an upwardly and rearwardly inclined letter-guiding portion which terminates in a vertically disposed portion near the rear of the partition.

9. In post-office furniture the combination with a frame, of shelves removably sustained thereby, backs for the shelves, and partitions sustained by the backs, each back having a trunnion at each end thereof, which is journaled in the frame, and also having a stop projection, and said frame having recesses to receive and coöperate with the stop projections to limit the swinging movement of the back and partitions.

10. In post-office furniture the combination with a frame, of shelves removably sustained thereby, a shelf back for each shelf independent thereof, partitions sustained by the shelf backs, and a holder at each end of each shelf, each holder being provided with a trunnion which is journaled in the frame, and a stop projection, said frame having recesses to receive and coöperate with the stop projections to limit the turning movement of the back.

11. In post-office furniture the combination with a frame, of shelves removably sustained thereby and each having a letter stop at its rear end, pivotally mounted shelf backs separated from the shelves, each shelf back being rabbeted on its front side to receive the letter stop of the corresponding shelf when the latter is in its operative position, and partitions carried by the shelf backs.

12. In post-office furniture, the combination with a frame, of shelves sustained thereby and an end rest rising from each end of each shelf, each end rest being formed of a loop of wire having its ends secured to the shelf, said wire at the central portion of the top of the end rest being bent to form an inwardly-facing strap-retaining hook.

13. In post-office furniture the combination with shelves, of a back for each shelf

having grooves therein situated at an angle with each other and a plurality of partitions associated with each shelf back, each partition having portions to enter two grooves 5 situated at an angle to each other.

14. In post-office furniture the combination with shelves, of backs for the shelves, each back having a groove extending longitudinally thereof and a plurality of grooves 10 intersecting the longitudinal groove, and partitions secured to each back, each partition having a portion to enter the longitudinal groove, and another portion to enter one of the intersecting grooves.

15. In post-office furniture the combination with shelves, of backs for the shelves, each back having a groove extending longitudinally thereof and a plurality of vertically disposed grooves intersecting the longitudinal groove, and wire partitions sustained by each back, each partition having a portion to enter both a vertical groove and the longitudinal groove, and means overlying said portions to hold them in the 25 grooves.

16. In post-office furniture the combination with shelves, of a back for each shelf, each back having a plurality of transversely disposed grooves formed in one face thereof, 30 wire partitions, each having a portion entering a transverse groove and a plate secured to the grooved face of the back and overlying said portions of the partitions to hold them in place.

17. In post-office furniture the combination with shelves, of a back for each shelf, each back having a longitudinal groove and a plurality of transverse grooves in one face thereof, wire partitions secured to each back, 40 each partition having two laterally extending portions to enter the horizontal groove and vertically extending portions to enter a transverse groove, and a plate secured to the grooved face of the back and overlying the portions of the partitions which occupy 55 the horizontal groove.

18. In post-office furniture, the combination with a frame, of swinging shelf-supporting members sustained thereby, shelves 50 removably supported by said shelf-supporting members, and shelf backs independent from the shelves also supported by said shelf-supporting members.

19. In post-office furniture, the combination with a frame, of a pair of suspenders pivotally connected at their upper ends to each side of the frame, shelf supports sustained by each pair of suspenders, shelves 55 slidably mounted in said supports, and shelf backs independent from the shelves secured to said suspenders.

20. In post-office furniture, the combination with a table having a table top, of a frame situated above the table comprising 60 two stationary uprights, a pair of swinging

suspenders pivotally secured at their upper ends to each upright, shelf supports connecting each pair of suspenders, and shelves 70 slidably mounted on said supports, whereby the relative position of the various shelf supports may be changed by swinging the suspenders.

21. In post-office furniture the combination with a table top extension having grooves on its upper face, of a follower 75 slidable longitudinally of said grooves and provided with an extension having locking flanges that are received in said grooves, and means to guide the follower in its sliding movement, the ends of said flanges having frictional engagement with the walls of the grooves when the follower is turned into an angular position thereby to lock the follower from movement.

22. In post-office furniture the combination with a table, of an extensible table top section having grooves in its upper face, a guiding strip sustained by said section between said grooves with the edges of said strip projecting partially over the grooves, 90 a follower slidable on and guided by said guiding strip, said follower having an extension provided with locking flanges that are received in said grooves whereby when said follower is turned into an angular position said flanges will frictionally engage the grooves thereby to lock the follower from moving.

23. In post-office furniture the combination with a table having a top section provided at one end with a fixed wall, of an extensible slide supported by said section and provided with an end rest which is spaced from the fixed wall and forms therewith a space to receive faced and sorted mail, and hooks secured to the fixed wall and the end rest to support the ends of a tape laid on said top section.

24. In post-office furniture, the combination with a table having a table top, of two 110 parallel metal strips set into the upper surface of the table top and each provided with a plurality of apertures, and a plurality of partitions each having a body and a wire frame encircling the sides and top of the body, the 115 ends of the wire projecting below the body to form feet to enter said apertures.

25. In post-office furniture the combination with a table having a table top, of an 120 assorting case situated above the table, and a plurality of adjustable partitions at each end of the table top, said partitions being comparatively short relative to the length of the table top and extending longitudinally thereof thereby to form on each side thereof 125 a plurality of spaces for receiving mail.

26. In post-office furniture the combination with a table having a table top, of a swinging arm at each side of the table top, two parallel metal strips set into the upper 130

surface of the table top at each end thereof and each provided with a plurality of apertures and a plurality of partitions having feet to enter said apertures, the outer ends 5 of said strips being bent upwardly to constitute stops for the swinging arms.

27. In post-office furniture the combination with a stand or a frame sustained thereby and comprising the bottom, sides and a 10 top which projects beyond the sides at each end, and an assorting case supported by said frame and having at each side a portion which overlies the projecting ends of the said top, and fastening means extending 15 through said projecting ends into the frame for detachably securing the parts together.

28. In post-office furniture, the combination with shelves, of backs for the shelves, each back having a plurality of grooves 20 formed in its top and bottom edge, a plurality of wire partitions sustained by said back, each partition being bent to form upper and lower legs which occupy grooves in the top and bottom of the back, and means for securing 25 said partitions to the back, the grooves holding the partition from lateral movement.

29. In post-office furniture, the combination 30 with a frame, of shelves removably sustained thereby, a shelf back for each shelf, each back having at each end a metal holder, means for securing said metal holders to the frame, and partitions sustained by the 35 shelf backs, said shelves being movable relative to the shelf backs.

30. In post-office furniture, the combination 40 with a frame, of shelves removably sustained thereby, a shelf back for each shelf, each back having at each end thereof a metal holder, means for pivotally connecting each holder to the frame, and partitions sustained by the shelf backs.

31. In post-office furniture, the combination with a frame, of shelves removably sustained thereby, a shelf back for each shelf 45 also supported by the frame, each shelf back having at each end thereof a metal holder provided with a trunnion about which the shelf back can turn, and partitions for the shelves secured to the shelf backs. 50

32. In post-office furniture, the combination with a frame, of shelves removably sustained thereby, a shelf back for each shelf also supported by the frame, each shelf back having at each end thereof a metal holder 55 provided with a trunnion about which the shelf back can turn, partitions for the shelves secured to the shelf backs, and means to limit the rocking movement of the shelf backs thereby to hold the partitions in position to permit a removed shelf to be inserted into place. 60

33. In post-office furniture, the combination with a frame, of shelves removably sustained thereby, a shelf back for each shelf, 65 and means movably secured to the frame for supporting the shelf backs in proper position.

34. In post-office furniture, the combination 70 with a frame, of shelves removably sustained thereby, a shelf back for each shelf, partitions for the shelves sustained by the shelf backs, and swinging members pivotally connected to the frame and by which the shelf backs are held in their desired 75 position.

In testimony whereof, I have signed my name to this specification, in the presence of two subscribing witnesses.

ROBERT T. BOURN.
